(57) **CLAIM**

The ornamental design for a computer display screen with mode selection screen interface, as shown and described.

DESCRIPTION

The sole FIGURE is a front view of the computer display screen with mode selection screen interface configured according to principles of the invention.

The outer edge of the computer display screen is understood to be congruent with the outer edge of the mode selection screen interface.

The broken lines in the drawing show a breadcrumb and graphical elements for enhancing overlaid icons that form no part of the claimed design.
